DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

26 Sheets Drawing. 47 Pages Specification

GENERAL FLOW DIAGRAM

A computer-aided method of developing a digitized multicolor design, including representations of arbitrary multicolor patterns inserted into arbitrarily defined areas of the design, and separating the color information in a color-by-color, row-by-row fashion to provide operating instructions for enabling a multicolor knitting machine to produce the design in fabric. The principal steps are shown in the general flow diagram. Steps 0 and 1 are known (U.S. Pats. Nos. 3,529,298 and 3,644,935). In step 2 an array of area label numbers is generated. In step 3 separate binary arrays are generated to represent the respective labeled areas. In step 4 arrays are generated to represent the selected color patterns in chosen areas. Color patterns may comprise solid or mixed colors. In step 5 binary arrays are generated to represent design elements separated by area and by color. In step 6 binary arrays are formed to show, for each color, where elements having that color are placed in the overall design. In steps 7, 8 and 9 the overall color separation arrays are arranged first in tandem, then are interleaved to represent binary instructions for operating the knitting needles in color-by-color, course-by-course fashion.

FIG. 13
AREA LABELS

FIG. 14
AREA LABEL ARRAY

A diagram of an area label array. The array is a 10x14 grid of cells. The first 13 columns are labeled with the number 1, and the 14th column is labeled with the number 3. An arrow labeled 'L' points to the 14th column. A 'ROW POINTER' arrow labeled 'i' points to the first cell of the 14th row. A 'POSITION POINTER' arrow labeled 'j' points to the second cell of the 14th row.

26 Sheets-Sheet 19

Diagram illustrating a 10x10 matrix with pointers *s*, *i*, and *j*.

The matrix is a 10x10 grid of zeros. A pointer *s* is shown pointing to the first element of the fourth row. A pointer *i* is labeled "ROW POINTER" and is pointing to the first element of the fourth row. A pointer *j* is labeled "POSITION POINTER" and is pointing to the second element of the fourth row.
